UNITED STATES PATENT OFFICE.

JOSHUA H. RYDER, OF BROCKTON, MASSACHUSETTS, ASSIGNOR OF ONE-HALF TO
GEORGE I. PETTENGILL, OF BOSTON, MASSACHUSETTS.

ATTACHMENT FOR SINKS, WASHTUBS, AND THE LIKE.

1,152,552.

Specification of Letters Patent.

Patented Sept. 7, 1915.

Application filed October 22, 1914. Serial No. 868,111.

To all whom it may concern:

Be it known that I, JOSHUA H. RYDER, a citizen of the United States, residing at Brockton, in the county of Plymouth and 5 State of Massachusetts, have invented new and useful Improvements in Attachments for Sinks, Washtubs, and the like, of which the following is a specification.

This invention relates to improvements in 10 attachments for sinks, wash tubs and the like.

More particularly it relates to covers, and it is an object of the invention to provide a cover that is easily and conveniently removable and one which comprises in itself 15 the attributes of a drain board and a wash board.

The invention also relates to details of construction by which these ends are attained in a superior manner, as set forth 20 hereinafter.

The accompanying drawings illustrate an embodiment of the invention and it is the intent of the patent to cover by the appended claims whatever features of patentable 25 novelty exist in the invention disclosed.

In the drawings: Figure 1 is a plan of one form of the invention, showing its application to a pair of wash tubs, to one of which 30 the invention is applied as a cover, and to the other as a wash board; Fig. 2 is a side elevation, in section on the line 2—2 of Fig. 1, showing the cover; Fig. 3 is a side elevation in section on the line 3—3 of Fig. 1, 35 showing the wash board; Fig. 4 is a front elevation, in section on the line 4—4 of Fig. 1; Fig. 5 is a section of a detail on a larger scale, showing the edge of the removable cover; Fig. 6 is a fragmentary view of the 40 bottom, showing details of construction, of the cover; Fig. 7 is a perspective view of certain details which may be considered as located near the lower left hand corner of Fig. 1, but embodying a modification of 45 structure; and Fig. 8 is a perspective view of other details which may be considered as located at the upper right hand corner of Fig. 2.

The drawings show a tub 10 whose front 50 wall is inclined in the usual manner and whose top is covered by a frame consisting of the back sill 11, the side pieces 12, the middle piece 13, and the front sill 14, which parts are joined together so that they can 55 rest smoothly on the top of the tubs which

are to be covered. In the form here represented the only ones of these parts resting directly on the tub walls are the two sills. The other pieces rest on the sills, being securely fastened thereto in any suitable way, 60 or being integral therewith, if desired. The central parts of the side and middle pieces may, if preferred, be further supported, to maintain them straight, by blocks 21, filling the space under them and having portions 65 21' that depend in the form of lugs adapted to engage the side walls of the tubs and so to prevent lateral displacement of the frame when it is in place on the tubs. In the present case a pair of such tubs are represented, 70 but it will be understood that the invention is applicable either to a single tub or to a group of any number arranged next to each other. In the latter case the extreme side 75 walls of the tubs may be covered by parts of the frame like the side pieces marked 12, the cross section of which is shown in Fig. 4, while each of the intermediary partitions may be covered by a middle piece 13, with a cross section also seen in Fig. 4, the former 80 having a single channel and the latter two channels. These channels serve as guides for the cover, which consists of a series of slats 30 preferably attached to each other by a continuous hinge of any suitable design, so that they are united into a stiff, flexible fabric. This is stiff in the direction of the length of the slats whose ends are guided in the said channels, so that they may 85 be drawn over the tub to cover it as seen at 90 the left in Fig. 1 and in Fig. 2; and is flexible in the direction of the breadth of the slats, so that when they are drawn out more or less it can bend as seen at the right in Fig. 1 and in Fig. 3. To aid in this movement handles 15 may be provided. The part 95 which is withdrawn may hang down over the front edge of the tub to whatever degree it is withdrawn; and it is contemplated that in some cases it will be wholly so withdrawn, except the last slat. To that end the last slat is provided with metallic plates or lugs 31 that engage lugs 31' positioned so as to fit loosely in a groove 24 cut through the 100 end portions of all of the slats, except the last, and to hold the last slat on the sill 14 and so hold the cover depending. However, it is a feature of the invention to provide for a positioning of the cover as a lining for the inside of the front wall of the 110

tub as illustrated in Fig. 3, for use as a wash board, the part not needed for lining this wall being allowed to hang down on the outside. This arrangement is effected by providing an opening through the bottom of the channel as clearly seen in Fig. 8 above the part 22 that is bent down.

The top of each slat 30 may carry a wire 20 of copper, galvanized iron or other suitable material, which may be of any convenient or suitable size and which may be set into the slat a little in order to hold it firmly against lateral displacement. These wires provide a series of metallic crests that make suitable corrugations for a wash board. There are various ways in which the slats may be fastened together without departing from the principles of the invention. One method is illustrated in detail in Figs. 5 and 6, which show similar hinge sections 16 provided for each end of each slat. Each of these is fastened to its slat by a screw 17 and is fastened to the adjacent hinge sections by pintles 18 thereby producing a continuous hinge joining all of the slats together. In the construction illustrated these hinges are at the extreme ends of the slat, and are in a position so that the plates of the hinges slide smoothly on the metal of the channel members 12 or 13 of the frame, the screws being placed so that their heads are outside of the channel. The hinges might, however, be placed elsewhere; and a different type of continuous hinge might be employed either in place of it or additional to it. For the purpose of showing such a different type, and also for showing a means for stiffening the center of the cover by causing each slat to be supported by its neighboring slats, I show a flexible tape 19 strung across the undersides of the slats from front to back in two places in each cover.

For the reception of the wires 20 a longitudinal groove may be formed in the top of each slat, and holes may be bored through the slats of sufficient size to receive the turned down ends of the wires. The ends may be clenched or upset underneath the slats. In Fig. 7 is shown a way of combining these two ideas which has practical merit in the direction of economy of construction and certainty of fastening of the parts together, in that the wire goes through the slat and through the hinged section 16 and takes the place of the screw 17 shown in Fig. 5, being headed over so as to hold the hinged section in its place, the part which forms the head lying in the countersunk part of the hinge section which would otherwise hold the head of the screw. Wires that are thus held taut in the groove at the top of the slat cannot be pulled out by rubbing them in the lateral direction on the top of the slat.

The frame as a whole may be held in position on the tubs which it covers by metallic lugs 21 arranged so as to project downward into each tub and to engage the walls thereof, being of rather stiff flexible sheet metal. These lugs may be bent a little, as necessary, so as to make a tight fit and prevent any looseness of the top on the tubs. This is a matter of commercial importance as it enables the apparatus to be made up in quantities, and carried in stock by dealers, with the certainty that the tubs of any purchaser can be fitted, notwithstanding slight variations which those tubs may exhibit from the precise measurement of a standard size. Further means for holding the frame in place on the top of the tubs is provided in the lugs 22 at the front edge which, projecting from the side pieces closely adjacent to the front sill 14, are adapted to lie against the front wall of the tub.

The apparatus is therefore easily placeable upon a tub or tubs and fixable in firm position thereon without boring into the relatively soft material of which such tubs are usually composed. The top of the front sill 14 is preferably rounded as indicated in the drawing so that the top may curve over its edge in either direction as illustrated in Fig. 8. When the apparatus has been adjusted so that it lies along the front wall of the tub as illustrated in Fig. 2 the force of gravity tends to hold it in position. It is however held firmly against upward displacement during its use as a wash board because the slat at the top of the bend engages the top sides of the channels in the pieces 12 and 13, and cannot rise farther. The slats may be set on their continuous hinges with spaces 23 between them if desired. Such an arrangement is illustrated and this makes the cover serviceable as a drain board when in place over the tub or over a sink; and it also lets water through from a dripping faucet, if there be such.

I claim as my invention:

1. An attachment for washtubs, sinks and the like comprising a frame adapted to rest on the walls of the basin thereof combined with a cover slidable backward and forward in the frame and adapted to bend around and depend from the front edge of the basin when drawn forward.

2. An attachment for washtubs, sinks and the like comprising a frame adapted to rest on the walls of the basin thereof combined with a series of slats, individually extending across the basin with their ends supported movably in said frame and collectively joined together by a continuous hinge, constituting a cover for the basin adapted to be drawn past an edge of the basin and to be bent around and to depend from said edge.

3. An attachment for washtubs, sinks and the like comprising a frame adapted to rest

on the walls of the basin thereof, having channels extending from front to back combined with a series of slats individually extending across the basin and guided in said channels, and hinges joining the slats together, said hinges having plate portions adapted to form the sliding bearing surfaces of the slats in the channel, and there being means located outside the channel to fasten said hinge plates to said slats.

4. An attachment for washtubs, sinks and the like comprising a frame adapted to rest on the walls of the basin thereof, combined with a series of slats individually extending across the basin with their ends guided by said frame, and wires on the tops of the individual slats and fastened individually thereto, the slats being joined together into a flexible cover for the basin.

5. An attachment for washtubs, sinks and the like comprising a series of slats adapted individually to extend across the basin thereof in one direction and collectively to extend across it in the other direction, means extending continuously in said other direction joining them together; and wires resting on the tops of individual slats, the ends of said wires penetrating through the slats

and through said joining means, fastening said slats and joining means together. 30

6. An attachment for washtubs, sinks and the like comprising a frame adapted to rest on the walls of the basin thereof, having channels; a flexible cover whose edges are guided by said channels in sliding from and 35 to the front; and means whereby said cover when withdrawn from said channels may extend down along the front wall of the basin as a washboard.

7. An attachment for washtubs, sinks and the like comprising a frame adapted to rest on the walls of the basin thereof, a flexible cover composed of slats some of which are separated from each other by short spaces 40 through which water may pass into the 45 basin and all of which are fastened together, the cover being withdrawable by sliding toward one of the edges of the basin and bending around it and hanging down therefrom.

Signed by me at Brockton, Mass., this 50

JOSHUA H. RYDER.
